UNITED STATES PATENT OFFICE.

RICHARD S. WARING, OF PITTSBURG, PENNSYLVANIA.

COMPOUND ELECTRIC CABLE.

SPECIFICATION forming part of Letters Patent No. 294,536, dated March 4, 1884.

Application filed July 20, 1883. (No model.)

To all whom it may concern:

Be it known that I, RICHARD S. WARING, a citizen of the United States, residing at Pittsburg, county of Allegheny, State of Pennsylvania, have invented or discovered a new and useful Improvement in Compound Electric Cables; and I do hereby declare the following to be a full, clear, concise, and exact description thereof, reference being had to the accompanying drawings, making a part of this specification, in which—like letters indicating like parts—

Figure 1 is a perspective view of my improved cable, and Fig. 2 is a transverse sectional view of the same.

15 My invention relates to certain improvements in metal-covered cables; and, in general terms, it consists of a cable having its insulated conducting-wires inclosed in separate tubular passages in a common body of metal, the wires being arranged in a novel manner or method, whereby flow of metal to form the inner walls of covering around the wires is facilitated, as hereinafter more fully described and claimed.

25 In the manufacture of lead-covered electric cables it is customary to make use of a "lead-press," so called, the insulated wires being passed through the tubular core or mandrel and through the die, the lead being applied 30 under pressure as an armor or covering to the wires within the die at the point or points of the wire-inclosing core; also, in the class of cables to which my present invention belongs, each wire is surrounded or inclosed and separated from others in the cable by continuous 35 solid or unbroken body or wall of metal, such metal covering serving the double purpose of a protective covering, shielding the insulated wires from external injury, and also 40 preventing disturbance from "electrical induction," so called. The protection thus afforded from induction is practically complete, and this is the case even though wires be in close proximity, closer than it has been found 45 to be practical to arrange them and secure the complete or intact lead covering requisite with means or methods heretofore employed. It is very desirable that as close and compact arrangement of wires be made as may be possible, in order to secure economy in the use of 50 lead, and also in space occupied by the cable. It is also desirable and often required that a

single cable should contain a considerable number of wires. A practical limit to the proximity of wires has been encountered, however, much short of what is desired. This has arisen from the difficulty of forcing sufficient amount of lead between the nipples of the mandrel to secure the essential condition of continuous unbroken enveloping of the wires 60 throughout the interior portions of the cable. This difficulty is greatly increased by multiplication of the number of wires arranged in a given space, and, as above stated, has imposed a practical limit upon the proximity of 65 the wires much short of what is desired and might otherwise be permissible.

The purpose of my present invention is to provide, in the arrangement of the wires in the cable, for much closer grouping of wires 70 than heretofore, and in so doing to secure the requisite characteristics of continuous unbroken covering or inclosing walls, with such degree of economy in construction as to bring a cable containing a comparatively large number 75 of wires within the limits of commercial success. To this end a cable is made by means of a press of the class above referred to, such cable having a homogeneous body of metal covering, A, by preference of lead, though other equivalent soft ductile metal or alloy may be employed capable of being formed into a homogeneous covering by means of a press. Within this body of metal are formed tubular passages a, by means of tubular nipples on the 80 core or mandrel, which nipples, individually considered, may be constructed and operated as commonly practiced in the art. Within these passages are inclosed the insulating conducting-wires e of the cable.

The special feature of construction in this connection is the relative arrangement of the wires within the lead body A, consisting of an arrangement of the wires in two rows, the wires e forming one such row and the wires e the 95 other row. The wires in the two rows alternate—that is, the wires in one row are at intervals about midway between the wires of the other, and the lines of the two rows are nearer together than the individual wires of each row, so that the space or distance between any two adjacent wires in the same row is greater than between any two adjacent wires taken in the two different rows; or, in other words, the pas-

sages through which lead flows from the exterior to the interior are widest or most open at the surface and most contracted in the center, where the lead, entering from opposite points, naturally meets and forms adhesive union under pressure around the inner surfaces of the wires. This provision in the arrangement of wires in a cable containing other than a single plane or row materially facilitates the flow of lead into the center, and insures intact homogeneous walls of covering in such interior, with closer proximity of wires than can be secured by methods of arrangement heretofore practiced. Substantially the same feature of grouping the wires in pairs of rows, with the adjacent wires of the two rows in closer proximity than the adjacent individuals of either row, may be incorporated into larger cables containing more than one pair of rows, and in so far as such compounding in a cable of this feature of construction may involve patentable invention not covered hereby I desire to reserve my right to file other applications for patents therefor, one such form and construction of compound cable being included in the subject-matter of a separate application filed even date herewith; also, in other applications filed this date I have described and claimed a new and useful construction of core or mandrel adapted to make the cables herein referred to.

In Patent No. 252,634, granted to me January 24, 1882, I have shown a cable and claimed the method of making the same, such cable having its wires arranged in two rows within a compound covering made up of separate

plates of lead united to form a tight covering. This construction of cable, with its compound or multiple-part cover, is not claimed herein; neither does it contain the same invention or meet the same requirements as the cable forming the subject of this invention, with its homogeneous and integral lead covering or body.

The difficulties overcome by the present invention are peculiar to cables having such a homogeneous body, and are not to any material extent characteristic of cables of the class described in the patent referred to.

I claim herein as my invention—

1. A compound electric cable having an integral homogeneous body or covering of lead, with insulated wires inclosed in separate passages therethrough, such wires being arranged in two rows, the adjacent wires of the two rows being in closer proximity than the adjacent wires of either row, substantially as set forth. 55

2. A compound electric cable having an integral homogeneous body of metal covering, with insulated wires inclosed in separate passages therethrough, such wires being arranged in two rows, the adjacent wires of the two rows 60 being in closer proximity than the adjacent wires in either row, and the wires of one row alternating in order of position with those of the other row, substantially as set forth.

In testimony whereof I have hereunto set my hand.

RICHARD S. WARING.
